UNITED STATES PATENT OFFICE.

CHARLES L. TINSLEY AND WILLIAM P. ROSE, OF BALTIMORE, MARYLAND.

BREECHING ATTACHMENT FOR THILLS.

SPECIFICATION forming part of Letters Patent No. 335,401, dated February 2, 1886.

Application filed July 14, 1885. Serial No. 171,588. (No model.)

To all whom it may concern:

Be it known that we, C. L. TINSLEY and W. P. ROSE, of Baltimore, in the State of Maryland, have invented certain new and useful 5 Improvements in Breeching Attachments for Thills; and we do hereby declare that the following is a full, clear, and exact description thereof, reference being had to the accompanying drawings, and to the letters of reference marked thereon, which form part of this 10 specification, in which—

Figure 1 is a plan view of our improved breeching attachment properly applied to the thills of a vehicle. Fig. 2 is a central longitudinal section of the same. Fig. 3 is a detail of one of the attaching devices.

This invention relates to breeching attachments for the thills of vehicles, and its object is to provide a holdback-bar that will also act 15 effectively to guard the vehicle from the kicking of a wild or vicious horse.

The invention consists, mainly, in securing by rigid connections to the thills, so as to stand a proper distance above the same a rigid semi- 20 elliptic holdback plate or bar; and it further consists in certain details of construction and arrangements hereinafter described, and pointed out in the appended claims.

Referring to the accompanying drawings by 25 letter, A designates the thills of ordinary construction, united by the transverse bar A', upon which the single-tree B is centrally pivoted in the usual way.

The attachment of each end of the hold- 30 back-bar to a thill being identical, the description of one attachment only is necessary.

C is the semi-elliptic holdback-bar, made 35 preferably of metal and in plate form with its edges vertical. The ends of said edges are 40 beveled toward points, for a purpose herein-after explained.

D and E are similar standard-supports secured to a thill a proper distance apart. The support D is composed of a horizontal flat 45 foot portion, d, bolted, riveted, or otherwise properly secured to the thill, a central portion, d', which curves upward and rearward from the foot d, and an upper horizontal plate portion, d'', which lies against the inner surface of 50 the end of the holdback-bar. The support E is composed of a foot, e, similarly secured to

the thill, a central portion, e', curving upward and forward from the foot, and a horizontal plate, e'', which lies against the outer surface of the end of the holdback-bar. The said 55 end and the plates d'' and e'' are properly riveted or bolted together, the end being beveled, as described, to prevent its edges making shoulders with the plates, which shoulders might irritate or wound the horse. The feet 60 d and e and plate portions d'' and e'' of the supports D and E run from the central portions, d' and e', in gentle curves, so that there may be no angles in the unions between the thills and the holdback-bar, which angles might wound 65 or irritate the horse. The supports D and E both incline inward from the thill, so that the ends of the holdback-bar are not vertically above the same, and so that the line of curve of the said bar may be continued by the front 70 support, D, from the end of said bar to the thill. By this means the rump of the horse can never come while backing into violent collision with the thill, and thereby loosen or break it. The holdback-bar stands suffi- 75 ciently above the thills to strike against the horse but a few inches below his tail, so that he gives a more equal pressure over the surface of the bar, and can never wound or abrade his legs, save in the act of kicking. The hold- 80 back-bar being rigid and horizontal when the horse is attached, the pressure in backing will tend neither to depress nor elevate the thills, as a flexible or inclined bar would do.

To guard against the horse being abraded 85 by the backward pressure, the holdback-bar is surrounded by a tight and sufficiently thick covering or sleeve, F, of leather, rubber, or other suitable material.

The invention has all the advantages of other 90 similar breeching devices, such as making the harness more simple by doing away with the breeching-strap and connections, allowing the horse to back with more force, rendering his attachment more simple, quick, and easy, &c. 95 It has, besides, the advantage that the bar presents an effectual barrier to the kicks of the horse reaching and injuring the body of the vehicle, and, as heretofore mentioned, the horse and thill are more effectually protected 100 from injury than by any previous-invented device for a like purpose.

We are aware that breeching devices attached to the thills to aid the horse in backing and to render the harness more simple have been patented, and such we do not claim, broadly.

5 We are aware that rigid holdback-bars have been connected to the thills of vehicles, and such we do not claim, broadly; but,

Having described our invention, we claim—

10 1. The combination, with the thills of a vehicle, of the rigid semi-elliptic holdback-bar C, secured to the thills in such manner that it will be horizontal when the horse is in place, and at its ends only, by curved bars that incline inward from the thills and form no angular corners therewith nor with the holdback-bar, and the tight sleeve F, of soft material, surrounding and padding the whole length of the holdback-bar, substantially as specified.

15 2. The combination, with the thills A A

and the standard-supports D and E, respectively provided with the feet d and e for the attachment to the thills, and the plates d² and e² for attachment to the holdback-bar and inclining inwardly from the thills, of the rigid 25 semi-elliptic holdback-bar C, having its end beveled to prevent forming shoulders with the plates d² and e², and the tight sleeve F, covering the holdback-bar, all constructed and arranged substantially as and for the purpose 30 specified.

In testimony that we claim the foregoing as our own we affix our signatures in presence of two witnesses.

CHAS. L. TINSLEY.
WILLIAM P. ROSE.
